UNITED STATES PATENT OFFICE

MARTIN KATZ, OF BROOKLYN, NEW YORK

MAIL CHUTE

Application filed February 26, 1930. Serial No. 431,456.

The present invention relates to mail chutes for office buildings and the like in which letter drops are provided for the several floors and lead through a common chute to a receiving box on a lower floor. More particularly the invention has reference to chutes in which the front walls thereof are longitudinally provided with removable glass panel sections adapted to be opened up for the relief 10 of the chutes in cases of accidental chokages.

The object of the invention is to provide an ornamental panel frame or sash construction in which the glass portions thereof are resiliently secured in position therein in order to avoid breakage of the glass when the 15 panels are removed and replaced with respect to the main body of the chute.

A further object is to facilitate the replacement of the panels by providing them with 20 guideways adapted to be engaged by the side walls of the chute.

For further comprehension of the invention, and of the objects and advantages thereof, reference is had to the following description 25 and accompanying drawings, and to the appended claims in which the various features of the invention are more particularly set forth.

Referring to the drawings in which similar 30 characters of reference designate like parts throughout the several views:

Figure 1 is an elevational view showing a portion of the front panels of a mail chute to which the present invention is applied.

Figure 2 is a sectional transverse view of 35 the paneled front and the back wall of the body of the chute.

Figure 3 is a plan view looking downwardly and shown partially in section.

Figure 4 is an enlarged sectional detail 40 view showing means for securing the marginal edges of the glass to the paneled frames or sashes.

Numeral 1 of the drawing indicates generally 45 the body of the mail chute consisting of the back wall 2 and the opposite side walls 3 all secured in well-known manner to the house wall of the building. The front wall of the chute, generally indicated by 4, is composed essentially of glass panels formed par-

tially in removable sections that include a mail drop for each of the several floors. As herein shown the panels containing the drop are held in connection with the chute by a cross bar 5, having hinge parts 6 at one end 55 thereof while its opposite end is adapted to be engaged and locked by a latch 7, all arranged in conventional manner. The mail drop is shown at 8 as projecting outwardly from and in integral relation with a panel section and is provided with a mail receiving slot 9 arranged to direct the mail matter over an inclined plate 10 and into the vertical passageway of the chute 1, and in case of chokage therein the section may readily be removed by opening up the cross bar 5. Inwardly extending side flanges 11 are also formed on the panel sections that engage the side walls 3 of the chute, the flanges thus serving to laterally align the removable front 60 wall sections.

For securing the glass to the panel sash members 12 the latter are preferably composed of extruded metal and provided on their inner faces with bearing seats 13 that engage the outer marginal surfaces of the glass against outward thrusts. Adjacent the marginal edges of the glass the seats of the sash members are provided with recesses 14 having undercut opposite side walls forming locking ledges adapted to secure one of the side edges or base sections 15 of a resilient clamp member, the opposite side edge 16 thereof being shaped to fold over and yieldingly engage the inner face of the glass in opposition to the bearing seats of the sash members. Between its side edges the clamp member is also provided with an inwardly curved intermediate portion 17 adapted to resiliently engage an edge of the glass and hold the same against edgewise displacement, this intermediate portion of the clamp member also serving in conjunction with the flanges 11 of the panel sections to form a guideway to receive the side walls 3 of the chute.

The clamp members thus formed are free to slide lengthwise of the recesses 14 of the sash members and are adapted to extend along the marginal edges of the glass for substantially its full length and to afford for the 85 90 95 100

latter a resilient connection that not only effectually secures the glass in position but also prevents injury thereto while being normally removed and repositioned for the purpose above described.

It is to be understood that the side edges 15 constitute base sections of the clamp members adapted by resilient action to be securely seated between the locking ledges of the recesses 14 of the sash members 12. Also, that the clamp members may be constructed in comparatively narrow widths to form clips disposed along the glass in spaced relation with one another, and, by their spring action, 20 the same may be inserted into the recesses at different points along the length of the sash members. As thus formed the clamp members consist of a single piece of spring metal folded in parallel relation as shown for the several purposes above described.

What I claim as my invention and desire to secure by Letters Patent, is:

1. In a glass receiving panel, a sash member having an inner face adapted to engage 25 the outer marginal face of the glass, a resilient clamp member having a marginal side edge secured in interlocking relation with the inner face of said sash member, the remaining portion of said clamp member being bent to 30 form a yielding stop engaging an edge of the glass and to fold over and engage the inner face thereof.

2. In a glass receiving panel, a sash member having an inner face adapted to engage 35 the outer marginal face of the glass, a resilient clamp member having a marginal side edge detachably secured in interlocking relation with the inner face of said sash member, the remaining portion of said clamp 40 member being bent inwardly to form a yielding stop engaging an edge of the glass and folded over to engage the adjacent inner marginal face thereof.

3. In a glass receiving panel, a sash member having an inner face adapted to engage 45 the outer marginal face of the glass, a recess formed along said inner face having undercut opposite side walls adapted to form locking ledges, a resilient clamp member having 50 one of its marginal side edges bent to yieldingly engage the locking ledges of said sash member and the remaining portion thereof being bent to form a yielding stop engaging 55 an edge of the glass and to fold over and engage the adjacent inner face thereof.

4. In a mail chute, a body member provided with back and side walls, a glass panel front detachably engaging the side walls of 60 said body member and including sash members having inner faces adapted to engage the outer marginal faces of the glass, flanges projecting inwardly from the inner faces of said sash members, resilient glass-securing clamp members having marginal side edges secured 65 to the inner faces of said sash members and

projecting inwardly therefrom in spaced relation to said flanges, the said spaces forming guideways for the side walls of said body member.

5. In combination with a glass receiving sash member having a seat engaging an outer marginal face of the glass, a recess formed in 70 said seat having side locking walls, and a spring clamp engaging the inner face of the glass and provided with a base section detachably secured within said recess.

6. In combination with a glass receiving sash member having a seat engaging an outer marginal face of the glass, a recess formed in 80 said seat having side locking walls, and a spring clamp engaging the inner face of the glass and provided with a yielding base detachably secured within said recess and adapted to be inserted therein or removed 85 therefrom intermediate the ends thereof.

7. In combination with a glass receiving sash member having a seat engaging an outer marginal face of the glass, a recess formed in 90 said seat, a spring clamp fixed at one end within said recess and extending outwardly therefrom to form a yielding stop for an edge 95 of the glass and folded over to form a clamp engaging the inner face thereof.

Signed at New York in the county of New York and State of New York this 18 day of February A. D. 1930.

MARTIN KATZ.
